UNITED STATES PATENT OFFICE.

GEORGE J. KELLEY, OF ATTLEBORO, MASSACHUSETTS.

KNIFE.

1,139,979.

Specification of Letters Patent.

Patented May 18, 1915.

Application filed November 10, 1914. Serial No. 871,391.

To all whom it may concern:

Be it known that I, GEORGE J. KELLEY, a citizen of the United States, residing at Attleboro, in the county of Bristol and State 5 of Massachusetts, have invented a new and useful Improvement in Knives, of which the following is a specification.

This invention relates to certain new and useful improvements in knives and relates 10 more particularly to improvements in the means for attaching the usual finishing sides or side plates to a knife.

The primary object of the invention is to provide means for attaching the sides of a 15 knife thereto without the use of solder. As heretofore practised solder has been used in securing the sides of pocket knives thereto, but this is objectionable, owing to the fact that after soldering refinishing is necessary, involving cleansing with acid solutions and consequent rusting of the steel 20 portions of the knife.

In the drawings Figure 1 is a side elevation of a pocket knife constructed in accordance with the present invention. Fig. 2 is a longitudinal sectional view. Fig. 3 is a plan view of one of the sides. Fig. 4 is an enlarged sectional view taken on the line 4—4 of Fig. 2, and Fig. 5 is a view similar 30 to Fig. 2, showing a modified form of the invention.

In proceeding in accordance with the present invention the plates 1 which are to be attached to the knife and are to form the 35 finished sides of the latter, are constructed with or drawn up to have a continuous flange 2 which follows the contour of the plate 1, both along the sides and ends of the latter and forms a permanent open main 40 pocket. The flange 2 at one end of the side plate 1 is extended to form a lip 3, which with the adjacent parts of the plate and flange forms a pocket. The flanges 2 do not grip the sides of the knife body nor one of 45 the ends of the latter, as shown in Figs. 4 and 2, but merely extend over the side plates 4 of the knife body so as to cover the knife body sides, but the gripping fingers, as shown in Figs. 2, 4 and 5, positively grip the 50 ends of the side plates of the knife body, so as to hold the side plates 1 thereon against movement with relation to the knife body.

The pockets that the lips 3 form are auxiliary or supplemental to the main pockets aforementioned.

The opposite ends of the side plates 1 do not possess lips 3, (Figs. 2, 3 and 5) but are formed adjacent their said opposite ends with apertures 5 which register with similar apertures 6 formed through the side plates 60 of the knife body and the latter, so that a rivet 7 may be passed through the aforementioned registering apertures and headed as shown in Fig. 2, to thus firmly connect the plates 1 to the knife body. The rivet 65 serves to hold the side plates 1 against movement and thus prevents movement of the lips 3, so that the side plates 1 are effectively secured against movement in all directions, due to the flange 2 which is of continuous character.

In Fig. 5 of the drawings, a slight modification of the invention is shown in which in lieu of the rivet 7 a bail 8 is employed, the ends of the bail passing into or through the 75 registering apertures 5 and 6. The bail can be used to attach to a chain or the like, or to a key ring. By providing the plates 1 at one of their ends with auxiliary pockets it is obvious that to attach the same to the usual 80 side plates 4 it is only necessary to slip one of the ends of the latter plates into the pocket, after which the plates 1 rest flush against the plates 4.

It will be apparent from the above that 85 solder is entirely dispensed with by use of the present invention, and that a simpler, less expensive, and time saving method is provided for securing the side plates to a knife.

In addition the flanges of the side plates 1 cover in part the sides and ends of the knife body and give to the knife a more finished and attractive appearance.

Having thus described my invention, I 95 claim as new and desire to secure by Letters Patent;—

In a knife having flat straight side plates, a pair of finishing side plates each having a permanent open main pocket formed by a 100 continuous bounding wall, said wall having an inward extension at one end which forms an auxiliary pocket whereby the knife side plates at their adjacent ends can be initially

22
placed in the auxiliary pockets and then be moved into the main pockets whereby the walls of the main pockets completely cover the side edges of the knife side plates and are connected to the latter without bending of the finishing plates or any part thereof, and means passed through registering apertures provided therefor in the finishing plates and knife at their opposite ends to se-

cure the opposite ends of the finishing plates 10 to the knife.

In testimony whereof I have signed my name to this specification in the presence of two subscribing witnesses.

GEORGE J. KELLEY.
